UNITED STATES PATENT OFFICE.

WILLIAM T. FARRELL, OF CHICAGO, ILLINOIS.

GAGE FOR MOLDINGS.

SPECIFICATION forming part of Letters Patent No. 360,213, dated March 29, 1887.

Application filed May 13, 1886. Serial No. 202,117. (Model.)

To all whom it may concern:

Be it known that I, WILLIAM T. FARRELL, of Chicago, in the county of Cook and State of Illinois, have invented a new and Improved 5 Gage for Use in Working Moldings, of which the following is a full, clear, and exact description.

The object of this invention is to promote accuracy in obtaining lines, angles, &c., in 10 working stone and to economize time and labor in such work.

The invention consists in the means substantially as hereinafter described and claimed.

Reference is to be had to the accompanying 15 drawings, forming a part of this specification, in which similar letters of reference indicate corresponding parts in all the figures.

Figure 1 is a plan view of my improved instrument, part of the scribe being broken 20 away to show the serrated or file-like inner surfaces of its sides. Fig. 2 is a section on the line xx , Fig. 1, the scribe having been removed. Fig. 3 is an edge view showing the 25 blade inserted in the head of the bevel, the said head being in section. Fig. 4 is a plan view of the circular base of a column with my improved instrument thereon in position for use. Fig. 5 is a section of part of such base 30 on the line yy in Fig. 4, and showing the instrument in side elevation and in dotted lines the profile of the molding to be worked. Fig. 6 is a face view of a block of stone on which a 35 molding is to be worked longitudinally, showing the instrument as applied to obtain the necessary lines. Fig. 7 is a side view of a molded cornice, taken in the direction of the arrow in Fig. 8, and showing the instrument as applied to obtain the miter-line for returning the molding. Fig. 8 is an end view of the 40 same, illustrating also the application of the plumb-point to ascertain if a member of the molding is level in the direction transverse to its length.

The bevel-stock A is provided with a longitudinal slot, a , at right angles to the main slot, 45 formed by the two sides of the stock, and on one of its side faces with a graduated sliding plate, B, and a pointer, b . The stem or shank b' , on which the pointer b is mounted, extends 50 through the said sliding plate and stock, and is provided on its opposite threaded end with a nut, C, for binding the disk B on the bevel at any desired point along the same. Intermediate of the nut C and graduated plate B,

between the two sides of the bevel, the stem 55 b' is provided with a catch or projection, c , for engaging the slotted end of the graduated blade D when the latter is inserted in the open side edge of the bevel-stock, the catch entering the slot of the blade. When the 60 blade D is swung either to the right or left, it will turn the pointer, and the angle formed by the blade D and the side edge of the bevel will correspond to the angle indicated by the pointer, as will be readily understood. 65

The scribe E is slotted longitudinally, as shown clearly in Fig. 7, so that it may ride on the blade D and bind thereon at any point. The inner faces of the sides of the scribe—that is, the parts of the scribe forming the 70 walls of the longitudinal slot therein—are serrated or file-like, as shown at a' , Fig. 1, to enable the operator, with but a slight pressure of the fingers, to bind the said scribe on the blade D when desired. The scribe is also, 75 by preference, provided with a swivel-socket, F, for the pencil G.

To obtain the lines of a longitudinal molding after the profile of the molding has been indicated on the end of the stone with the aid 80 of the mold or pattern in the usual manner, the bevel A, carrying the blade D and scribe E, is placed on the top bed of the stone, as in Fig. 6, and the point of the pencil placed on the point at the end of the stone from which 85 the line is to start, and the instrument is then moved or slid along the stone, the bevel being held down on the top bed, and the scribe will trace the line as it moves along. The pencil is then shifted to where the next line is to be 90 traced, and so on as before. With the inner surfaces of the sides of the scribe serrated, as before mentioned, a slight pressure of the fingers will suffice to firmly bind it on the blade D while the line is being drawn, and by reason of the swivel-socket F the pencil will accommodate itself to the slight irregularities of 95 the stone.

To obtain the lines for working a molding on a circular base, the bevel is placed on the 100 top bed of the stone, the same as in the instance above mentioned, and the pencil placed on the stone at a distance from the top corresponding to the distance therefrom of the member to be worked, and the instrument is swung around 105 on the top bed till the line is completed around the stone. The pencil is then moved down to where the next line is to be traced and the

operation just described repeated. The advantages of the instrument in obtaining these lines will be readily apparent to practical stone-cutters.

5 In a recess in the end or head of the bevel is fitted the two-part revolving socket H for the blade D, the parts h h of the said socket being made gradually wider toward the bottom, and at the extreme bottom edge are each 10 formed with an outwardly-extending lip or tongue, (shown in section in Fig. 3,) so that when the blade D is inserted in the socket H, as shown in said figure, the two parts h h will be forced outward, as will readily be understood. It is evident that when the blade D is inserted only part way in the socket H and turned the said socket will turn with it; but when the blade is forced home in the said 15 socket it will be firmly held therein, and the socket will be wedged against the wall of the recess in which it is seated.

A great desideratum, also, with stone-cutters is to quickly get a correct miter-line when about to continue a molding on the end of a 20 cornice or other stone after the molding has been worked on the face of the stone, or, as it is technically termed, "returning" the molding. To accomplish this with my invention, the slotted end of the blade D is inserted in 25 the head H at the proper angle relatively to the longitudinal axis of the bevel, as in Figs. 7 and 8, and the scribe E placed loosely on the said blade, the bevel being placed on the top member of the molding at or near the end 30 thereof, so that the point of the pencil will be 35 on the point from which the miter-line is to start.

The bevel and blade are held firmly in the position with one hand, while with the other 40 the scribe is passed over the face of the stone, and, being permitted to ride freely on the blade, forward or backward, up or down, it will trace 45 the miter-line accurately over the molded face no matter what the contour of the same. Should the size of the stone be such that the 50 miter-line will be too long for the scribe to trace it from the position of the instrument at the top of the stone, the line is traced as far as the length of the scribe will permit, and the 55 instrument is brought down to the end of the line thus traced and the scribe again started to complete the line.

It is not absolutely necessary that the socket H should revolve or that it be divided, as an ordinary socket in the head will sometimes answer for holding the blade D. The revolving head is preferred, however, as it facilitates obtaining the miter-line when the miter is to be other than forty-five degrees, and difficulty 60 is experienced, except by expert stone-cutters, in obtaining such lines.

In practice the pointer b and nut C are preferably within the plane of the sides of the bevel, so as not to interfere with the easy working of the bevel on its side.

To ascertain whether a member of the molding is level in the transverse direction, I have

provided the pivoted plumb-point I on the end of the bevel A. If a member is not correct in this respect, it is readily discerned when 70 the bevel is placed thereon, the plumb-point swinging to the right or left of the vertical center of the end of the bevel when the member is other than true—as, for example, at i in Fig. 8, where I have shown in full lines a member not true and in dotted lines the member as it should be.

In obtaining the lines for a straight molding, as in Fig. 6, the rod or "straight-edge" is usually employed, and while this is generally satisfactory it will at times be found convenient to employ my improved instrument.

It will be understood that the invention above described is capable of many uses other than those above set forth.

Having thus fully described my invention, I claim as new and desire to secure by Letters Patent—

1. The combination, with a bevel-stock having a socket in its head and a longitudinal slot 90 at right angles to the main slot formed by the two sides of the stock, of an adjustable sliding stem carrying a catch and carrying on its top a disk and pointer, and a slotted blade, substantially as shown and described. 95

2. An instrument of the character described, comprising a bevel-stock constructed with a socket in its head and a longitudinal slot at right angles to the main slot, a sliding stem carrying a catch, and a slotted blade adapted 100 to engage either the catch on the sliding stem or the head-socket, as required, substantially as shown and described.

3. An instrument of the character described, comprising a bevel-stock constructed with a 105 divided rotating head forming a socket, a sliding stem carrying a catch, and a slotted blade adapted to either the socket-head or the sliding stem and catch, substantially as shown and described. 110

4. An instrument of the character described, comprising a bevel-stock constructed with a divided rotating head, the two parts of said head being wider at the bottom than at the top, a sliding stem carrying a catch, a sliding 115 plate and pointer mounted on the stem, a slotted blade, and a scribe, substantially as shown and described.

5. The combination, with a bevel provided with a rotating head and a graduated sliding 120 plate and pointer, of a slotted blade and a scribe, substantially as shown and described.

6. An instrument of the character described, comprising the bevel A, the sliding plate and pointer B b, and the head, H, of the blade D, 125 and scribe E, substantially as shown and described.

7. The scribe E, having a swivel-socket, F, for the reception of a pencil, and having the inner surfaces of its sides serrated, substantially as shown and described. 130
